US00D877417S

(12) **United States Design Patent** (10) **Patent No.:** **US D877,417 S**
(45) **Date of Patent:** **** Mar. 3, 2020**

(54) **COSMETIC COMPACT**

(71) Applicant: **Mary Kay Inc.**, Addison, TX (US)

(72) Inventors: **Jenny DeMarco Staab**, Addison, TX (US); **Alexa Hanna**, Addison, TX (US)

(73) Assignee: **Mary Kay Inc.**, Addison, TX (US)

(**) Term: **15 Years**

(21) Appl. No.: **29/668,421**

(22) Filed: **Oct. 30, 2018**

Related U.S. Application Data

(62) Division of application No. 29/627,397, filed on Nov. 27, 2017, now Pat. No. Des. 836,842.

(51) **LOC (12) Cl.** **28-03**

(57) **CLAIM**

The ornamental design for a cosmetic compact, as shown and described.

DESCRIPTION

FIG. 1 is a top perspective view of a cosmetic compact; FIG. 2 is a front view of the cosmetic compact shown in FIG. 1; FIG. 3 is a back view of the cosmetic compact shown in FIG. 1; FIG. 4 is a left side view of the cosmetic compact shown in FIG. 1; FIG. 5 is a right side view of the cosmetic compact shown in FIG. 1; FIG. 6 is a top view of the cosmetic compact shown in FIG. 1; FIG. 7 is a bottom view of the cosmetic compact shown in FIG. 1; and, FIG. 8 is a bottom perspective view of the cosmetic compact shown in FIG. 1.

1 Claim, 8 Drawing Sheets
